Attorney.

UNITED STATES PATENT OFFICE.

SAMUEL G. HILL, OF MUSCATINE, IOWA.

WAGON-SPRING.

SPECIFICATION forming part of Letters Patent No. 252,035, dated January 10, 1882.

Application filed March 22, 1880. (Model.)

To all whom it may concern:

Be it known that I, SAMUEL G. HILL, a resident of the city of Muscatine, county of Muscatine, and State of Iowa, have invented a certain new and useful Improvement in Applying Springs to Vehicles; and I do hereby declare the following to be a full, clear, and correct description of the same, reference being had to the annexed drawings, making a part 10 of this specification.

This invention relates to that class wherein the bodies of vehicles are hung by means of supports or standards surrounded by spiral springs.

15 My improvement consists in the bolsters having their ends projecting beyond the sides of the vehicle-body, and having fitted thereon or therein vertical standards or posts surrounded by spiral springs, in combination with trans- 20 verse straps bolted or otherwise secured to the bottom of the vehicle, with projecting ends passing over the standards or posts of the bolsters.

25 My improvement also consists in the novel construction and combination of the parts, hereinafter more fully set forth.

30 On the drawings, Figure 1 represents a side elevation of a wagon, the nearest wheels of which are omitted in order the better to exhibit the nature of my invention. Fig. 2 is a cross-section through the line $\alpha\alpha$ of Fig. 1. Fig. 3 is a similar view, with the spring-standards in inverted positions; and Fig. 4 shows the application of a double instead of a single set of springs.

35 A represents a wagon-body; B B', the wheels; C C', the axles, and D D' the bolsters thereof. The ends of the latter are made to project beyond the sides of the wagon-body, and have fitted thereon or therein vertical spring-standards e e', &c. The upper ends of these standards pass through or are secured to the ends of straps f f', which are bolted or otherwise secured across the bottom of the wagon-body on lines immediately above the axles.

40 The standards e are each encircled by a spiral spring, g, and these springs sustain the whole weight of the wagon-body. As the latter is being loaded the springs become com-

pressed, while at the same time the free ends of the standards are forced through the perforations that are made in the strap ends. An extra heavy load will compress the springs to such an extent as to cause the wagon-body to rest directly on the bolsters, thus preventing the breaking of the springs by too great a pressure.

45 For heavy wagons double springs should be employed, and for this purpose a cross-piece, h, should be fitted over the ends of the bolsters, as in Fig. 4, or lugs should be constructed on the sides of the same.

The object of shouldering the transverse bars f f' is to afford side supports for the wagon-body and provide means for the passage of the side standards through the same, as shown.

50 It will also be seen by reference to Fig. 2 of the drawings that the lower ends of the standards are formed with sockets, which are passed over the ends of the bolster D, so as to connect the parts more readily.

55 Having described my invention, what I claim as new, and desire to secure by Letters Patent, is—

1. In means for hanging the bodies of vehicles, the combination of the bolsters having 75 their ends projecting beyond the sides of the vehicle-body, and having fitted thereon vertical standards or posts surrounded by spiral springs, and the transverse straps with shouldering-extensions h, bolted to the bottom of the 80 vehicle, with its projecting ends fitting over the standards or posts of the bolster, substantially as described.

2. In means for hanging the bodies of vehicles, the combination of the bolsters D D' 85 with vertical standards e and coil-springs g, the transverse straps f f', with shouldering-extensions h, and the cross-pieces h', fitted on the bolsters, substantially as and for the purposes set forth.

90 In testimony whereof I have hereunto signed my name.

SAMUEL G. HILL.
